UNITED STATES PATENT OFFICE.

BENJAMIN W. JOHNSTON, OF ROSEDALE, ALBERTA, CANADA, ASSIGNOR OF ONE-HALF
TO BERTON A. McEWEN, OF DRUMHELLER, CANADA.

LATCH.

Application filed March 5, 1925. Serial No. 13,358.

This invention relates to improvements in latches for doors and other hinged members, an object being to provide a latch which will securely hold a door in closed position 5 and which will be released simultaneously with either the pushing or pulling action when opening the door.

Another object of the invention is the provision of a latch as above stated which is 10 simple in construction, efficient in use and which may be adapted for use upon screen doors, public halls, theaters and so forth.

With the above and other objects in view, the invention further includes the following novel features and details of construction, to be hereinafter more fully described, illustrated in the accompanying drawings and pointed out in the appended claims.

In the drawings:—
20 Figure 1 is a fragmentary sectional view illustrating the latch in use.

Figure 2 is an enlarged fragmentary section of the same partly broken away.

Figure 3 is a detail perspective view of 25 the keeper.

Figure 4 is a sectional view showing a modified form of the invention.

Referring in detail to the drawings wherein like characters of reference denote corresponding parts, the reference character 10 indicates a portion of a door, for example a screen door, the frame of the door being provided with a stop 11 against which the free edge of the door engages to limit swinging 35 movement in one direction.

Secured to the door by screws 12 or similar fastening devices is a bracket 13. This bracket is provided with an offset portion or extension 14 which forms a latching shoulder 40 which is adapted to engage a keeper plate 15. One end of the plate 15 is secured to the door frame by screws or other fastening devices 16 and the opposite end of the plate is relatively offset and is spaced from the frame. The plate is provided with an 45 opening so as to form a shoulder 17 at one edge of the opening, the latching shoulder 14 of the bracket 13 engaging this shoulder 17 and when so engaged will prevent outward swinging movement of the door.

Pivotedly secured at one end of the bracket 13 as indicated at 18 is a latch bar 19. In Figures 1 and 2, this bar is substantially L-shaped and is positioned so that one of its 55 arms 20 will engage the free end of the

keeper plate and move the latter out of the path of the latching shoulder 14. To accomplish this the outer end of the latch bar 19 has extending therethrough the shank of a knob 21, the inner end of this shank being secured to the shank 22 of a knob 23. The knob 23 is located upon the outside of the door and the shank 22 extends through the door and through a plate 24 secured upon said door.

A pull upon the knob 23 for the purpose of pulling the door 10 outward, will move the latch bar 19 pivotally and cause the arm 20 of the said bar to engage the free end of the keeper plate 15 so as to move the shoulder 17 of said plate out of the path of the latching shoulder 14 as previously mentioned. A push upon the knob 21 from the inside of the door will accomplish the same function so that the act of opening the door 75 will at the same time release the latch. When closing the door the latching shoulder will engage the shoulder 17 of the keeper plate and the latter will engage the arm 20 of the latch bar 19 so as to properly position the said bar.

For the purpose of preventing release of the latch from the outside of the door, when desired, there is pivotally secured to the latch bar 19 as shown at 25, a locking finger 85 26. When the free end of this finger is positioned against the bar as shown by the dotted lines in Figure 1, the latch bar will be held against pivotal movement.

In the form of the invention illustrated 90 in Figure 4, the construction is the same except that the latch bar has its long arm 27 extended substantially across the width of the door and its free end slidingly engaging the inner face of the door. The free end of the latch bar is supported within a guide 28. By pushing upon the arm 27 of the latch bar at any point throughout its length, the said bar will be moved pivotally to actuate the latch in the manner previously described. In this form of the invention the door could not be opened from the outside. The latch shown in Figure 4 is especially adapted for use upon the doors 95 of small theaters, halls or other places of public gathering.

The invention is susceptible of various other changes in its form, proportions and minor details of construction and the right is herein reserved to make such changes as 110

properly fall within the scope of the appended claims.

Having described the invention what is claimed is:—

5. 1. The combination with a hinged door, of a bracket carried thereby, an extension provided upon the bracket, a relatively yieldable keeper mounted in the path of movement of and engaging the extension, a pivoted bar carried by the bracket and including an offset end portion arranged to engage the keeper whereby when said bar is moved the bracket will be released, and means carried by the bar for holding the latter against pivotal movement.
10. 2. The combination with a hinged door, of a bracket carried thereby, an extension provided upon the bracket, a relatively stationary yieldable keeper mounted in the path of movement of the extension, said keeper comprising a plate having an opening therein and a free opposite end adapted to be engaged by the bracket extension, a pivoted bar carried by the bracket and including an offset end portion arranged to engage the opposite end of the keeper plate whereby when said bar is moved the bracket will be released, and means carried by the bar for holding the latter against pivotal movement.
15. 3. The combination with a hinged door, of a bracket carried thereby, an extension upon the bracket, a relatively yieldable keeper mounted in the path of and engaging the extension, a bar pivotally secured to the bracket, and including an offset end portion arranged to engage the keeper whereby the latter may be moved to release the bracket and means whereby the bar may be actuated, and means carried by the bar for holding the latter against pivotal movement.
20. 4. The combination with a hinged door, of a bracket carried thereby, an extension upon the bracket, a relatively yieldable keeper mounted in the path of and engaging the extension, a bar pivotally secured to the bracket, and including an offset end portion arranged to engage the keeper whereby the latter may be moved to release the bracket, and means slidably mounted on the door and operable from either side thereof, and connected with said bar for moving the latter pivotally.

and means located upon opposite sides of the hinged door and operatively associated with the bar whereby the latter may be moved pivotally, and means carried by the bar for holding the latter against pivotal movement.

5. The combination with a hinged door, of a bracket carried thereby, an extension upon the bracket, a relatively yieldable keeper mounted in the path of and engaging the extension, a bar pivotally secured to the bracket, and including an offset end portion arranged to engage the keeper whereby the latter may be moved to release the bracket, means located upon opposite sides of the hinged door and operatively associated with the bar whereby the latter may be moved pivotally and means whereby the bar may be held against pivotal movement, and means carried by the bar for holding the latter against pivotal movement.

6. The combination with a hinged door, of a bracket carried thereby, an extension upon the bracket, a relatively yieldable keeper mounted in the path of and engaging the extension, a bar pivotally secured to the bracket, means carried by the bar and engaging the keeper whereby the latter may be moved to release the bracket, means located upon opposite sides of the hinged door and operatively associated with the bar whereby the latter may be moved pivotally and a locking finger pivotally secured to the bar and engageable with the door whereby the bar may be held against pivotal movement.

7. The combination with a hinged door, of a bracket carried thereby, an extension upon the bracket, a relatively yieldable keeper mounted in the path of and engaging the extension, a bar pivoted on said bracket, and including an offset end portion arranged to engage the keeper whereby the latter may be moved to release the bracket, and means slidably mounted on the door and operable from either side thereof, and connected with said bar for moving the latter pivotally.

In testimony whereof I affix my signature.
BENJAMIN W. JOHNSTON.
